(57) **CLAIM**

The ornamental design for a drinkware lid with handle as shown and described.

DESCRIPTION

FIG. 1 is a side perspective view of a drinkware lid with handle according to the present disclosure.

FIG. 2 is a top plan view thereof.

FIG. 3 is a side elevation view thereof.

FIG. 4 is a front elevation view thereof.

FIG. 5 is a front perspective view thereof.

FIG. 6 is a bottom plan view thereof.

FIG. 7 is a side perspective view of the drinkware lid with handle used in a surrounding environment with a drinkware container.

FIG. 8 is a front elevation view thereof; and,

FIG. 9 is a side elevation view thereof.

The shade lines in the Figures show contour and not surface ornamentation. The broken lines in the Figures show portions of the drinkware lid with handle that form no part of the claimed design. The broken lines in FIGS. 7-9 show the surrounding environment of a drinkware container that forms no part of the claimed design.

1 Claim, 6 Drawing Sheets
